UNITED STATES PATENT OFFICE.

ALFRED B. FOWLER, OF BEVERLY, MASSACHUSETTS, ASSIGNOR TO UNITED SHOE MACHINERY CORPORATION, OF PATERSON, NEW JERSEY, A CORPORATION OF NEW JERSEY.

SEWING MACHINE.

Original application filed May 21, 1919, Serial No. 298,589. Divided and this application filed September 25, 1920, Serial No. 412,653. Renewed August 27, 1925.

To all whom it may concern:

Be it known that I, ALFRED B. FOWLER, a citizen of the United States, residing at Beverly, in the county of Essex and State of Massachusetts, have invented certain new and useful Improvements in Sewing Machines; and I do hereby declare the following to be a full, clear, and exact description of the invention, such as will enable others skilled in the art to which it appertains to make and use the same.

The present invention relates to sewing machines and more particularly to mechanisms for actuating the back gage of an inseam shoe sewing machine.

The principal object of the invention is to provide a back gage actuating mechanism for inseam shoe sewing machines of novel and improved construction and mode of operation. To this end, the features of the invention consist in certain constructions, arrangements and combinations of parts hereinafter described and claimed, the advantages of which will be obvious to those skilled in the art.

The several features of the invention will be clearly understood from the following description and accompanying drawings in which Fig. 1 is a sectional elevation looking from the right and taken on a plane just to the right of the needle segment of an inseam shoe sewing machine embodying the features in their preferred form, and Fig 2 is a detail sectional elevation of the back gage and back rest locking mechanism.

The inseam shoe sewing machine illustrated in the drawings may be and preferably is the same as the machine illustrated and described in applicant's co-pending application Serial No. 298,589, filed May 21, 1919, of which the present application constitutes a division. This machine, as illustrated, is provided with a curved hook needle 2, a needle guide 4, a thread finger 6, a looper 8, a back gage 10, a back rest or bunter 12, and a vertical rod 14 which at a predetermined point in the final cycle of operations of the machine is moved upwardly, and which upon throwing the machine into operation is depressed.

The needle is secured in the usual manner to a needle segment 16 which is pivotal-

ly mounted on a shaft 18 and is actuated by a link 20 having one end pivotally connected at 22 with the needle segment and its other end pivotally connected with a cam actuated lever 24.

The back rest or bunter 12 comprises a roll mounted on a forwardly spring pressed slide 26. The back gage 10 is connected as hereinafter described to a locking slide 28. The slides 26 and 28 are provided with means for locking them together, which means may be and preferably is the same as disclosed in applicant's co-pending application, Serial No. 254,104, filed September 14, 1918. The back gage is formed on the forward end of a carrier 30 which is connected by a link 32 with the back gage locking slide 28, one end of the link being pivoted upon a stud 34 secured to the carrier 30 and its other end being pivoted on a stud secured to the slide 28. The back gage carrier is guided by means of a bolt or pin 36 secured to the frame of the machine which extends through a horizontal slot in the carrier. The free end of an arm 38 is pivotally connected with the stud 34 which arm is secured to a rock shaft 40. An arm 42 is pivoted upon the shaft 40 and is connected with the arm 38 by a torsion spring 44 which is normally under no tension. During the work piercing movement of the needle 2, the back gage is first caused to lightly engage the work and is then pressed against the work under increasing pressure by means of a stud 46 on the needle actuating link 20

that engages the arm 42 and through the torsion spring 44 and arm 38 thus actuates the back gage. The back gage and back rest are locked in engagement with the work at the limit of this stroke of the needle and until the needle returns to the limit of its loop drawing stroke. In order that the back gage may not interfere with the feeding of the work, means is provided for retracting the back gage after the needle has reached the limit of its loop drawing movement. To this end, the rock shaft 40 carries an arm 47, the free end of which is engaged by a lug 48 projecting from a sleeve 50 that is mounted to slide on the vertical rod 14. A spring 52 is coiled about the rod 14 and is interposed between the lower

- end of the sleeve 50 and a collar 54 secured to the rod. When the back gage is unlocked at the limit of the loop drawing stroke of the needle, the coiled spring 52 acts through 5 the connecting mechanism to retract the back gage. As the torsion spring 44 is under no tension at this time it will not interfere with this action of the coiled spring 52 and, also, as the strength of the coiled 10 spring is considerably less than that of the torsion spring 44, the coiled spring will not interfere with the action of the torsion spring in advancing the back gage during the work piercing stroke of the needle.
- 15 The upward movement of the rod 14 upon stopping the machine increases the tension of the coiled spring 52, which ensures the complete retraction of the back gage at this time.
- 20 To lock the slides 26 and 28 against backward movement a locking bar 56 is provided having a rectangular opening at its upper end through which the slides pass. The upper and lower surfaces of the opening 25 in the bar 56 are bevelled slightly at their edges as indicated in Fig. 2, and the bar is arranged at right angles to the slides in such a position that a tilting movement of the bar will force the two slides together and lock them against backward movement with relation to the locking bar. The upper end of the locking bar is received 30 in a recess in a slide 57 rigidly secured to the machine frame. The lower end of the locking bar 56 is engaged by a spring pressed 35 plunger 58 which forces the bar in a direction to hold a cam roll 60 at the lower end of the bar in contact with a cam 62 on the cam shaft of the machine. The plunger 58 40 at its end remote from the locking bar is mounted to slide in the hub of a screw 64 mounted in the machine frame and at the end which contacts with the locking bar is provided with a head between which and 45 the hub of the screw 64 its actuating spring 66 is located. The arrangement of the locking bar 56, the spring pressed plunger 58 and the cam 62 is such that movement of the lower end of the bar by the cam against 50 the action of the spring pressed plunger unlocks the slides 26 and 28, while a movement of the lower end of the locking bar under 55 the influence of the spring pressed plunger locks the slides.
- 55 The slide 26 is pressed toward the shoe by a spring pressed arm 68 journaled at its lower end in the frame of the machine

and having its upper end in engagement with the rear end of the slide.

While it is preferred to employ the specific 60 construction and arrangement of parts illustrated and described, it is to be understood that this construction and arrangement is not essential except so far as specified in the claims, and may be changed or modified 65 without departing from the broader features of the invention.

The nature and scope of the present invention having been indicated, and a machine embodying the several features of the 70 invention in their preferred form having been specifically described, what is claimed is:—

1. An inseam shoe sewing machine having, in combination, stitch forming devices 75 including a curved hook needle, a back gage movable towards and from the work, means for locking the back gage against the work and for unlocking the back gage, a spring acting on said gage, means for increasing 80 the tension of the spring to press the back gage against the work and for decreasing the tension of the spring after the gage is locked in position, and means for retracting 85 the back gage.

2. An inseam shoe sewing machine having, in combination, stitch forming devices including a curved hook needle, a back gage movable towards and from the work, means for locking the back gage against the work 90 and for unlocking the back gage, a spring acting on said gage, means for increasing the tension of the spring to press the back gage against the work and for decreasing the tension of the spring after the gage is 95 locked in position, and a retracting spring tensioned by the movement of the back gage against the work for retracting the back gage.

3. An inseam shoe sewing machine having, in combination, stitch forming devices 100 including a curved hook needle, a back gage movable towards and from the work, means for locking the back gage against the work and for unlocking the back gage, a spring 105 acting on said gage, means for increasing the tension of the spring to press the back gage against the work and for decreasing the tension of the spring after the gage is locked in position, a retracting spring for 110 retracting the back gage, and means acting on stopping the machine to increase the tension of said retracting spring.

ALFRED B. FOWLER.
